SUSPENSORY

Filed Jan. 22, 1929

Wilhelm P. Schmidt, ^{Inventor}
By, Carlos P. Griffin
Attorney

UNITED STATES PATENT OFFICE

WILHELM PAUL SCHMIDT, OF SAN FRANCISCO, CALIFORNIA

SUSPENSORY

Application filed January 22, 1929. Serial No. 334,234.

This invention relates to a suspensory for acute diseases of the male organs, and its object is to produce a suspensory which will be made of a longitudinally corrugated impervious material to prevent it from adhering to the organs and which will for the same reason permit any moisture to drain down to the bottom of the sac.

Another object of providing the corrugated sac is to allow for ventilation and expansion of the sac.

A still further object of the invention is to provide a flap for the removal of the organ when the patient desires to urinate.

Other objects of the invention will be apparent as the description proceeds.

An embodiment of the invention is shown in the accompanying drawing in which the same reference numeral is applied to the same portion throughout the several figures of the drawing and of which there may be modifications.

Figure 1 is a front view of the suspensory and supporting belt.

Figure 2 is a front view of the corrugated sac on a larger scale, and

Figure 3 is a horizontal sectional view of the sac on the line 3—3 Figure 2.

The numeral 1 indicates the belt which has two ordinary buttons or snap glove fasteners 2, 3 at its wider end, while an adjusting buckle 4 is provided at the other end.

There is also a strap 5 which is passed through the buckle 4 and which strap has the two snap fasteners 5 and 6. The snap fasteners 2, 3 and 5, 6 cooperate with four snap eyes 7 to 10 inclusive on a flat band 11.

The flat band 11 has a bellows like longitudinally corrugated tube 12 secured thereto, and into which the male organ can be placed. This corrugated tube has some holes 13 at different places in its upper portion to allow a certain amount of ventilation, and it also has a flap 14 which may be secured in the

position shown in Figure 1 by two snap fasteners 15 and 16.

The flap 14 is larger than the opening in which it is secured by an amount shown at 14', Figure 2 to insure any moisture passing down inside the suspensory, the flap being opened whenever the patient desires to urinate.

At the top of the sac the corrugations are arched over and two holes 18 permit the support of a suitable bandage with a tape passing through the holes. Opening 17 indicates opening for the entrance of the organ into the sac as shown at Figure 2.

Having thus described my invention, what I desire to secure by Letters Patent of the United States is as follows, but modifications may be made in carrying out the invention as shown in the drawing and in the above particularly described form thereof, within the purview of the annexed claims.

I claim:

1. A suspensory for males comprising a flat band, and a longitudinally cylindrical corrugated retaining sac carried by the flat band, and an opening in the front of the sac, which is closed by a flap and an adjustable belt to which said band is detachably secured.

2. A suspensory for males comprising a flat band, connected and supported by an adjustable belt to the flat band, and secured by an adjusting buckle, a longitudinally corrugated retaining sac carried by the flat band, an opening on the front of the sac and a flap to cover said opening and an opening in the back of the flat band, to permit the insertion of the organ into the sac.

3. A suspensory for males comprising a detachable supporting belt to pass around the body, a longitudinally corrugated sac connected to a flat band at the front, an opening having a flap in the upper part of said sac, snap fasteners to secure said flap and a series of ventilating holes in the upper portion of said sac and an opening in the back of the

flat band, to permit the insertion of the organ into the sac.

4. A suspensory of the class described comprising a flat band adapted to be detachably secured to an adjustable body belt, a tube having longitudinal corrugated walls closed at the lower end and fixed to said band, an opening through the band to said tube, an opening in the front of said tube having a closing flap, snap fasteners to secure said flap, and a series of ventilating holes in the upper portion of said tube.

In testimony whereof I have hereunto set my hand this 11th day of January, A. D. 1929.

15 WILHELM PAUL SCHMIDT.
